HIGH TENSITY LAMP

Milton Fletcher, 85 New York Ave.,
Congers, N.Y. 10020

Filed June 27, 1966, Ser. No. 2,824

Term of patent 14 years

(Cl. D48—20)

FIGURE 1 is a perspective view of a high tension lamp showing the light part extended from the base and attached by suction cup to a wall surface, and

FIG. 2 is a perspective view taken from the opposite direction but with the light attached by suction cup to the top of the base.

I claim:

The ornamental design for a high tension lamp, substantially as shown.
